ELECTRIC LAMP

Eugene Schwarz, Alexandria, Ind., assignor to The
Mantle Lamp Company of America, Chicago,
Ill., a corporation of Illinois

Application October 2, 1940, Serial No. 359,311

5 Claims. (Cl. 240—81)

The present invention relates to electric lamps of the type having a main source of light for normal use and an auxiliary source of light adapted to provide subdued illumination for use as a night light or the like. In such lamps the lamp stand usually has a distended portion or bulge partly formed of a translucent material, within which the bulb for the auxiliary light is housed.

In devices of this type access to the bulb within the receptacle formed by the lamp stand has been 10 difficult and whenever replacements had to be made it was usually necessary to loosen the rigid structure of the lamp and to disconnect its wiring.

It is an object of the present invention to provide an electric lamp having a main source of light and an auxiliary source of light wherein said auxiliary source of light is readily accessible without need to dismantle the lamp.

More specifically it is an object of the present invention to furnish an electric lamp having an 20 auxiliary source of light disposed below the main source of light and housed in a receptacle formed by integral parts of the lamp structure and including a portion of a light transmissible material wherein replacement of said auxiliary source of 25 light and of said portion of a light transmissible material can readily be made without loosening the rigid connection of the elements constituting the lamp structure.

It is another object of the present invention to furnish a lamp head adapted to be mounted upon a lamp stand and having a main source of light and an auxiliary source of light disposed within a receptacle formed by integral parts of the lamp head structure and including a portion of a light transmissible material, wherein the source of light in the interior of said receptacle is readily accessible and the portion of light transmissible material may readily be replaced without interfering with the rigid connections of the elements forming 40 the structure of said lamp head.

According to the invention a lamp of the type referred to includes a receptacle which houses the auxiliary source of light and which comprises a base portion upon which is mounted a shell of a light transmissible material. A dome having an outer diameter smaller than the inner diameter of said shell is rigidly supported from said base portion at approximately the level of the upper end of said shell. Said dome has a number of openings directly above said shell from which protrude removable pins or screws which keep said shell in proper position. The socket for the main source of light is mounted on top of said dome and is preferably of a diameter smaller than the diameter of said shell of light transmissible material. The base portion of the receptacle may be an integral part of the lamp stand or it may be provided with screw threads at the bottom adapted to engage corresponding screw-

threads in a lamp stand upon which the complete device is to be mounted.

The invention will best be understood by reference to the accompanying drawing which illustrates a preferred embodiment thereof by way of example, and wherein

Fig. 1 shows a lamp incorporating the present invention, and

Fig. 2 shows a detail of the lamp illustrated in Fig. 1 on an enlarged scale and partly in section.

The lamp shown in Fig. 1 has a pedestal 1 of cast iron, brass or any other suitable material, upon which is mounted a tubular stem 2. At its upper end stem 2 has a distended portion or bulge 3 including an annular wall or shell 4 of translucent material and enclosing a small electric bulb (Fig. 2). Upon portion 3 is mounted a reflector cup 5 which houses the socket for the main source of light represented by large bulb 6. Reflector cup 5 carries reflector 7 which in turn supports lamp shade 8.

Referring to Fig. 2 the distended portion or bulge 3 of the lamp stand comprises a base part 9 of cup shape terminating with an open tubular extension 9a at the bottom. The upper end of base part 9 is shaped to form an annular horizontal area 9b upon which is supported annular shell 4 which is made of a translucent material such as frosted glass, porcelain or the like. Area 9b is surrounded by an external rim or flange 10 formed on the edge of base portion 9 against which shell 4 may bear and which determines the proper position of said shell. Three rigid supports 11 (only two visible in Fig. 2) rise within the shell 4, from horizontal area 9b of base part 9 to which they may be attached by screws 12. They support a dome 13 of brass or the like with which they may form an integral part, as shown, and which is disposed at approximately the same level as the upper end of shell 4.

A lamp socket 14 holding auxiliary lamp 17 is mounted within the interior of base part 9 in any suitable manner, for instance by bracket 15 which is secured to the inside wall of base part 9 with the aid of switch 16 that controls the operation of bulb 17. Auxiliary lamp 17 of low wattage is preferably disposed at approximately the same level as translucent shell 4. A socket 18 for the main bulb 6 is mounted upon dome 13 with the aid of screws 19 and reflector cup 5 is held in position between the bottom of said socket and a flat annular area 13a formed at the upper end of dome 13. Reflector cup 5 is of such size laterally that it protrudes nowhere beyond the open width of shell 4. A switch 20 is provided to control main bulb 6. Any conventional wiring may be employed in connection with switches 16 and 20 that allows either or both of the bulbs to be turned on at will.

The lower end of dome 13 may terminate slightly below the upper end of annular shell 4. Dome 13 and shell 4 are so related in size that the maximum outside diameter of dome 13 is slightly smaller than the smallest inside diameter of shell 4 and movable stops are provided for holding shell 4 in place, for instance, dome 13 may have a number of holes directly above said shell which are engaged by screws or pins 21 that extend over, and retain said shell in its proper position upon base portion 9.

If it is desired to have access to bulb 17 within the receptacle formed by base portion 9, annular shell 4 and dome 13, it is only necessary to remove screws 21 and to lift shell 4. Due to the fact that the maximum external diameters of dome 13 and reflector cup 5 are smaller than the smallest internal diameter of translucent shell 4 it is possible to lift shell 4 past dome 13 whereupon the interior of the receptacle is freely accessible. Thus bulb 17 may be exchanged without the need to dismantle parts of the lamp or loosen the rigid connection of the metallic elements that form the structure of the lamp. Likewise, if it is necessary to replace shell 4, for instance in case said shell has broken, a new shell may readily be slipped down over reflector cup 5 and dome 13 into its proper position on base portion 9 after screws 21 and main bulb 6 with reflector 7 have been removed and there is no need to remove any main parts of the lamp assembly such as dome 13, reflector cup 5 or socket 18 which would involve the disconnecting of the wires that supply power to the bulbs. To this end switch 20 may be located at a reduced portion 5a of reflector cup 5 and may protrude only to such an extent laterally that its free length together with the diameter of the reduced portion 5a of reflector cup 5 is shorter than the open width of shell 4.

Other modifications of the embodiment described above within the scope of the present invention will readily occur to those skilled in the art.

Bulge 3 may form an integral part of stem 2 of the lamp by base portion 9 being a direct continuation of tubular stem 2. Such a structure may be produced by a process known as slush casting. On the other hand bulge 3 may form a separate detachable lamp head. In the latter instance screw threads may be provided in the tubular extension 9a of base portion 9 adapted to engage corresponding screw threads provided in the top of stem 2. Additional subsidiary lamps may be supported from part 3 such as arms or brackets 22 holding auxiliary lamps of the candle type and which may be rigidly attached to the sides of base portion 9. In this case base portion 9 and brackets 22 may be produced as a single integral piece by slush casting and also dome 13 and supports 11 may be made as a single integral piece so that the lamp head comprises a minimum number of individual parts.

While I have shown my invention in the particular embodiment above described I do not limit myself thereto, and many equivalents may be devised without departing from the scope of the appended claims.

Having thus described my invention what I claim is:

1. An electric lamp having a standard, said standard including an extended portion forming a base, a dome rigidly supported from and a distance above said base, a shell of light transmis-

sible material resting loosely upon said base and extending upward to said dome to form together with said base and said dome a substantially closed receptacle, an auxiliary lamp socket disposed within said receptacle, and a main lamp socket mounted above said dome, the maximum outer diameters of both said dome and said main lamp socket being smaller than the minimum inner diameter of said shell.

10 2. An electric lamp having a standard, said standard including an extended portion forming a base, a dome rigidly supported from and a distance above said base, a shell of light transmissible material resting loosely upon said base and extending upward to said dome to form together with said base and said dome a substantially closed receptacle, an auxiliary lamp socket disposed within said receptacle, a main lamp socket mounted above said dome, the maximum outer diameters of both said dome and said main lamp socket being smaller than the minimum inner diameter of said shell, and a number of movable stops protruding from said dome above the upper end of said shell.

15 25 3. An electric lamp having a standard, said standard including a cup-shaped portion forming a base, a dome rigidly supported from and a distance above said base, a shell of light transmissible material resting loosely upon said base and extending upward to said dome to form together with said base portion and said dome a substantially closed receptacle, an auxiliary lamp socket disposed within said receptacle, a main lamp socket mounted upon said dome and a reflector cup surrounding said main lamp socket and held in position between said dome and said main lamp socket, said reflector cup having a portion of reduced diameter and a switch provided at said reduced portion, the maximum outer diameters of said reflector cup, said main lamp socket and said dome being smaller than the minimum inner diameter of said shell.

20 40 45 4. An electric lamp head adapted to be mounted upon a lamp standard, including a base portion, a dome rigidly supported from and a distance above said base portion, a shell of light transmissible material resting loosely upon said base portion and extending upward to said dome to form together with said base portion and said dome a substantially closed receptacle, an auxiliary lamp socket disposed within said receptacle, and a main lamp socket mounted upon said dome, the maximum outer diameters of both said dome and said main lamp socket being smaller than the minimum inner diameter of said shell.

50 55 5. A lamp head adapted to be mounted upon a lamp standard including a base portion, a dome rigidly supported from and a distance above said base portion, a shell of light transmissible material resting loosely upon said base portion and extending upward to said dome to form together with said base portion and said dome a substantially closed receptacle, an auxiliary lamp socket disposed within said receptacle, a main lamp socket mounted upon said dome, a reflector cup surrounding said main lamp socket and held in position between said dome and said main lamp socket, the maximum outer diameters of said reflector cup, said main lamp socket and said dome being smaller than the minimum inner diameter of said shell, and a number of adjustable stops protruding from said dome above said shell.

EUGENE SCHWARZ.
